Primary Examiner — Ian Simmons*Assistant Examiner* — Shannon Morgan(74) *Attorney, Agent, or Firm* — Daniel N. Smith(57) **CLAIM**

The ornamental design for a beverage container holder, as shown and described.

DESCRIPTION

FIG. 1 is a top perspective view of a beverage container holder showing my new design;

FIG. 2 is a side elevational view thereof;

FIG. 3 is a top plan view thereof;

FIG. 4 is a bottom plan view thereof;

FIG. 5 is a rear elevational view thereof;

FIG. 6 is a front elevational view thereof;

FIG. 7 is another top perspective view thereof; and,

FIG. 8 is a rear perspective view thereof.

The broken lines in FIGS. 7 and 8 of the beverage container holder are for the purpose of illustrating environment, and form no part of the claimed design.
